UNITED STATES PATENT OFFICE

HERBERT S. POWELL, OF UTICA, NEW YORK

MUFFLER-CUP-ASSEMBLING MACHINE

Application filed March 30, 1928. Serial No. 266,067.

My invention relates to a muffler cup assembling machine and I declare the following to be a full, clear, concise and exact description thereof sufficient to enable anyone skilled 5 in the art to which it appertains to make and use the same, reference being had to the accompanying drawings in which like reference characters refer to like parts throughout the specification.

10 The object of the invention is to provide a machine adapted to aid in assembling the cups of a muffler used in connection with the exhaust gases of an internal combustion engine of automobiles. In mufflers of the 15 cup type, the several cups fit together tightly at their contacting edges to aid in holding them together. With the aid of this machine each successive cup as it is superimposed 20 bottom-side up upon the one next below will have its free peripheral edge forced into fitting relation with the contiguous bottom surface of the cup next below with one blow of the hammer employed in the device. Moreover, there is also means for feeding 25 upwards through the several cups the stay rods that are used also to aid in holding the several cups and end members of the muffler in assembled relation.

The object will be understood by referring 30 to the drawings in which:

Fig. 1 is a perspective view of the device showing parts in section.

Fig. 2 is a detail view somewhat enlarged showing a rack in fragment and gear in mesh 35 which are employed.

Referring more particularly to the drawings the device embodies a frame comprising upright rods 1, 1 adapted to support at their upper ends a cross support or strut 2. The 40 lower end of each of rods 1 is held in a socket 3 that is made integral with floor standard 5.

An adjustable shelf 6 is mounted on rods 1, 1 some distance above standard 5. Shelf 6 has depending bushings 9, 9 that are fixed 45 to rods 1, 1 by set bolts 10, 10.

A countersunk annular recess 11 is made in the upper surface of shelf 6, which recess is adapted for the disposition of the periphery of the first cup 12 turned bottom-side up. 50 An enlarged central aperture is made through

the center of shelf 6 for the projection therethrough of stay rods 15, 15 used to hold the several cups 12 of the muffler together. The lower ends of rods 15, 15 rest in sockets made in members 16, 16 formed integral with vertically movable platform 20.

Platform 20 has apertures at 21, 21 whereby it can slide on rods 1, 1 and is attached to vertically movable hanger 22, by adjustable rods 23, 23. Sleeves 24, 24 are mounted to rods 23 in such manner that rods 23, 23 can slide therethrough, whereby there is permitted a given amount of motion of hanger 22 independent of platform 20. Hanger 22 is reduced at 25, 25 to provide thinner portions for the projection of rods 23, 23 therethrough.

Hanger 22 is secured to the lower end of gear rack 30. The upper end of gear rack 30 projects through an open recess in stationary cross strut 2, whereby it is permitted to move in a vertical plane. A cable 35 is attached through an eye bolt 36 fixed to the upper end of rack 30 and passes over a pulley 37 supported on shaft 38 carried in hangers 39, 39 fastened to any overhead structure. A weight 41 is attached to the free end of cable 35 whereby to aid in drawing gear rack 30 normally upward.

In order to force rack 30 downward against the pull of weight 41 there is provided a gear 45 that is in mesh with said rack 30. Gear 45 is carried to turn with shaft 50 having bearings in bracket arms 51, 51 formed integral with strut 2. Shaft 50 and gear 45 mounted thereon is turned by hand wheel 52 which is fixed to the end and adapted to turn with shaft 50.

A counter weight 55 is attached to platform 20, by means of a cable 56 that passes over pulley wheel 57 mounted to turn on shaft 38 whereby to pull normally upward support 20. Rods 15, 15 carried on said platform 20 will work upward gradually as cups 12 are built up on each other to form a muffler. Set bolts 60, 60 are screw mounted to sockets 61, 61 of platform 20 and are adapted to engage standards 1, 1 with more or less degree of friction, whereby to govern the amount of

freedom with which said platform 20 will slide on standards 1, 1.

In operation platform 20 is forced downward manually. Stay rods 15, 15 are disposed through central aperture 14 in stationary shelf 6 with their ends resting in sockets made in members 16, 16 of platform 20. A cup 12 is placed in recess 11 of shelf 6, bottom side up and over stay rods 15, 15, which are permitted to move upward through the corresponding apertures made in the bottom surface of cup 12. A second cup 12 is then placed on the first cup over stay rods 15, 15 which have been allowed to move upward still further. Hanger 22 is then lowered into contact with the adjacent surface of second cup 12 by turning hand wheel 52 whereby to force the flared edge 60 of said cup 12 over the contiguous bottom edge of the first cup 12 and into close adherence therewith. Then each cup 12 is piled up successively on its adjacent cup 12 until the muffler is completed. Platform 20 carrying stay rods 16, 16 in vertical position thereon will move upward automatically, as cups 12 are built upward upon each other, under the influence of weight 55, whereby to be in position to project rods 16 through the corresponding apertures made in each cup 12 as each is successively placed on top of the next lowermost cup 12.

Set bolts 10, 10 may be projected clear through sleeves 9 and standards 1, 1, whereby to make a very rigid support for shelf 6.

Having thus described my invention what I claim is new and desire to secure by Letters Patent is as follows:

1. In a cup assembling machine, stationary means for holding a cup, movable means for pressing a second cup into close contact with the first named cup and means for projecting stay rods through said cups.
2. In a cup assembling machine, a member for holding a cup, a movable member for pressing a second cup into close contact with the first cup and a hanger connected to said movable means, whereby to project stay rods through said cups.
3. In a cup assembling machine, means for supporting a cup, a movable member for forcing a second cup into close contact with the first named cup, gear means for actuating said movable member, and means connected with said movable member for projecting stay rods through said cups.
4. In a cup assembling machine, means for supporting a cup, a movable member for forcing a second cup into close contact with the first named cup, means for actuating said movable member, and other means connected with said movable member for projecting stay rods through said cups.

In testimony whereof I have affixed my signature.

HERBERT S. POWELL.
